UNITED STATES PATENT OFFICE.

FRITZ KUKE, OF BERLIN, GERMANY.

MULTIPLE PLUG AND SOCKET FOR PORTABLE TELEPHONE STATIONS.

Application filed May 28, 1927, Serial No. 195,111, and in Germany November 25, 1926.

This invention relates to telephone stations, more particularly to multiple plugs and sockets for portable telephone stations, which may be plugged in at any place where 5 sockets are provided.

The object of the present invention is to provide multiple plugs and sockets of an improved type as to compactness, durability and easiness of use, and not liable to break- 10 age.

The multiple socket comprises a body portion of insulating material, a central bolt serving for one lead and, at the same time, for bolting to the body portion, a plurality 15 of contact springs, each of them insulated from the bolt and one another. A cap provided with a central hole of suitable width covers the contact bolt and springs and leaves room for the plug to enter. This latter resembles plugs as usual with telephone switchboards. It contains a central bolt, to 20 which are threaded, concentrically, so many metal sleeves, insulated from each other and the central bolt, as leads are to be provided. 25 The sleeves are held in position by a nut screwed to the inside end of the central bolt. A handle of insulating material is screwed to the outer metal sleeve. Its back end contains a hole through which the phone cord 30 is threaded. The strain cord of the latter is tied to a pin inside of the hollow handle. A special feature of the plug is that the central bolt is provided with a hole to receive the upper slit part of the central contact bolt of 35 the socket. By this means the plug may be designed much shorter than the usual plugs are. The back end of the plug handle is provided with a wire helix for the protection of the phone cord, the ends of which helix are 40 held by metal rings so that they cannot cut into the cord running through.

Referring to the drawings:

Figure 1 is a view of the interior of the socket, the base and cover in section.

45 Figure 2 is a detailed view of the bolt and the different contact springs of the socket showing the assemblage of these parts.

Figure 3 is a sectional view of the multiple-way plug.

50 The socket (Figures 1 and 2) contains a base 1 and cover 2 of insulating material. In the upper central hole of the cap 2 is seen a cylindrical contact bolt 3. The upper slit part of this bolt is divided from the middle 55 part by a shoulder, while the lower threaded part passes through the base plate 1 to which

it is fastened by a pair of nuts 4. The middle part of the bolt carries an insulating sleeve 3' flattened on one side, and the bolt and insulating sleeve are threaded through 60 the contact springs 5, 6, and 7, which are divided from each other by insulating washers. The holes of said contact springs are again flattened on one side, the flattened part being 65 shifted in each spring with respect to the flattening of the holes of the other springs, so that the springs are distributed round the bolt in such a way that they cannot touch each other, except if a special break contact 70 is to be provided as shown at 5, 5'. The screws 8 are used to fasten the leads of the telephone cable. They may be provided on the contact springs themselves or, as shown in Figure 1, on special metal pieces 3'', 5'', 6'', 7'' which are in touch with the bolt 3 and the respective contact springs and are held by the bolt 3 in the same way as said springs. The binding screws 8 might as well be replaced by soldering tabs. 75

Figure 3 shows the multiple-way plug. 80 The metal bolt 9, hollow at the tip, is run through the tubular parts 10, 11 and 12, individually insulated. The outer ends of parts 10 and 11 are thickened, while part 12 is threaded on its outer surface. All three— 85 10, 11, 12—may possess circular grooves to secure fast clamping of the contact springs (5, 6, 7) of the socket. The insulated central bolt 9 serves for holding together the parts 10, 11, 12 by means of the nut 13, as well as 90 the bail 14 carrying a split pin 14' to which the strain cord of the flexible telephone cable (not shown) is tied. The outer end of bolt 9 is hollow to receive the contact pin 3 of the socket; both the split part of pin 3 and the hollowed bolt 9 are so long as to allow to 95 serve as a safe guide for the plug. The screws 15 are used to clamp the leads of the cable to the different parts of the plug. A handle 16 of insulating material is screwed to the metal body 12. Where the cable or cord enters, the handle carries a steel wire helix 17 which avoids abrupt bending of the cord. The ends of helix 17 are held in metal rings 17', 17'' against chafing of the phone 105 cord.

Having now particularly described and ascertained the nature of my said invention and in what manner the same is to be performed, I declare that what I claim is:—

110 1. The combination of a multiple way plug and socket, particularly for switching in port-

- able telephone stations; in the plug a central metal bolt and a plurality of individually insulated concentrical contact pieces slipped over, and fastened on, said bolt; said bolt and contact pieces cooperating with a central contact pin and a corresponding number of individually insulated bent contact springs fastened in the wall socket around, and fixed on, said contact pin.
- 10 2. The combination of a multiple way plug and wall socket; in the plug a central metal bolt and a plurality of individually insulated concentrical contact pieces, one or more of these contact pieces provided with circular grooves; in the socket a central pin holding in position a plurality of bent contact springs, insulated from each other and from said pin; said contact springs engaging, with their contact faces, in the grooves of said contact pieces of the plug.
- 15 3. The combination of a multiple way plug and socket, a plurality of bent contact springs held by a central contact pin in the socket; cooperating therewith in the plug, a central bolt and a suitable number of contact pieces, concentrical with said bolt; an insulating plug handle screwed on the outer contact piece, a steel wire helix fastened in the open back end of said plug handle, metal rings holding the ends of said helix to avoid chafing of the phone cord run through the protecting helix into the interior of the plug.
- 20 4. The combination of a multiple way plug and socket; in the plug a plurality of contact pieces slipped over a central metal bolt, said bolt containing in its front end a cylindrical bore, apt to receive a slit contact bolt placed amid the wall socket and carrying around it a suitable number of bent contact springs.
- 25 5. The combination of a multiple way plug and socket; in the plug a hollow-tipped contact bolt carrying several individually insu-

lated concentric contact pieces; in cooperation therewith, in the socket, a plurality of bent contact springs and a slit central contact pin; said pin having its upper slit part separated from the middle by a shoulder; an insulating sleeve on the middle part of said pin, said bent contact springs threaded over said insulating sleeve; a base plate of insulating material, a pair of nuts screwed to the lower part of the contact pin clamping together the whole assembly of contact springs, at the same time fixing it to the base plate; a cap of insulating material covering the contacting parts of the wall socket; an opening in said cover giving access to the plug to get into engagement with the respective parts of the socket.

6. The combination of a multiple way plug and socket; in the plug a hollow-tipped central contact bolt, a plurality of insulated contact rings slipped over said bolt; corresponding thereto, in the socket, a suitable number of bent contact springs insulated from each other by the interposition of insulating washers; said bent springs and washers slipped over the middle part of a slit contact pin; an insulating sleeve interposed between said contact pin and contact springs; a flattening on the outer side of said sleeve, corresponding flattenings in the holes of said bent contact springs, the flattening of the hole of each spring being shifted with respect to the flattenings of the other springs; a pair of nuts screwed to the lower part of said contact pin, clamping together and to the insulating base plate the whole assembly of contact springs; a cap of insulating material with an opening in its top, allowing the plug to enter.

Dated this 4th day of May, 1927.
In testimony whereof I affix my signature.

FRITZ KUKE.
